US00D858915S

(12) **United States Design Patent** (10) Patent No.: **US D858,915 S**
Beaudreault et al. (45) Date of Patent: ** Sep. 3, 2019

(54) **FABRIC CARE APPLIANCE**

- (71) Applicant: **WHIRLPOOL CORPORATION**, Benton Harbor, MI (US)
- (72) Inventors: **James Beaudreault**, Lincoln, RI (US); **Adam Richard Brown**, Holland, MI (US); **Lucien Bourbeau**, Assonet, MA (US); **Matthew B. Conn**, Granger, IN (US); **Gregory A. Ferro**, Elkhart, IN (US); **Christopher A. Gregory**, St. Joseph, MI (US); **Nicholas Koukourakis**, Stevensville, MI (US); **Andrew S. Lawrence**, St. Joseph, MI (US); **Eamon C. Lyons**, Somerset, MA (US); **Mark W. Schulz**, Benton Harbor, MI (US)
- (73) Assignee: **Whirlpool Corporation**, Benton Harbor, MI (US)

(**) Term: **15 Years**

(21) Appl. No.: **29/679,085**

(22) Filed: **Feb. 1, 2019**

Related U.S. Application Data

- (63) Continuation of application No. 29/605,910, filed on May 31, 2017, now abandoned.

(57) **CLAIM**

The ornamental design for a fabric care appliance, as shown and described.

DESCRIPTION

FIG. 1 is a front perspective view of a fabric care appliance according to our design;
FIG. 2 is a front elevation view thereof;
FIG. 3 is a rear elevation view thereof;
FIG. 4 is a left side elevation view thereof;
FIG. 5 is a right side elevation view thereof;
FIG. 6 is a top plan view thereof; and,
FIG. 7 is a bottom plan view thereof.

(Continued)

The broken lines showing portions of the fabric care appliance form no part of the claimed design.

1 Claim, 7 Drawing Sheets
